UNITED STATES PATENT OFFICE.

JESSE E. MELTON, OF ALMONT, NORTH DAKOTA.

CALENDAR.

1,363,427.

Specification of Letters Patent. Patented Dec. 28, 1920.

Application filed January 19, 1918. Serial No. 212,617.

To all whom it may concern:

Be it known that I, JESSE E. MELTON, a citizen of the United States, and a resident of Almont, in the county of Morton and 5 State of North Dakota, have invented a new and useful Improvement in Calendars, of which the following is a specification.

My invention relates to improvements in 10 calendars, and it consists in the constructions, and arrangements herein described and claimed.

An object of my invention is to provide a 15 calendar having a removable calendar pad, each page of the pad having ruled and numbered spaces on the back for written memoranda.

Another object of the invention is to provide a calendar as described, having a removable calendar pad with combined rings 20 for holding the pages together and a brace formed with the rings to stiffen the otherwise flexible pad.

Another object of the invention is to provide a calendar as described, including a 25 pocket for holding the removable calendar pad, the edges of the pocket being reinforced to prevent tearing when the calendar is used as a wall pocket for temporarily preserving small articles and various data.

30 Other objects and advantages will appear in the following specification, reference being had to the accompanying drawing in which:

Figure 1 is an elevation of a calendar including the removable pad constructed in accordance with my invention.

Fig. 2 is a vertical section on the line 2—2 of Fig. 1, and

Fig. 3 is a detail view showing the manner 40 of forming the calendar pocket.

In carrying out my invention, I provide a back 1 upon which a mask 2 is pasted and additionally secured by the eyelet 3 at the top, by means of which the calendar may be 45 hung upon the wall. The mask 2 has an opening 4 through which the picture 5 is visible. The picture 5 is pasted on the back 1 and may be that of a local scene or consists of any appropriate subject.

50 A slit 6 is cut into the mask 2 below the opening 4, and the ends of the slit 6 are prevented from tearing when the calendar is employed in a manner to be explained, by reinforcing pieces 7 which are glued in 55 place in the formation of the calendar. These reinforcing pieces 7 may be of any

suitable material and preferably consist of pieces of stiffened linen such as is usually employed in constructions of this kind.

Formed between the back 1 and the mask 60 2 is a pocket 8. The pocket 8 consists simply of a sheet of paper or other suitable material, folded at one side of the center so as to make one end longer than the other. The long end 9 is pasted to the back of the 65 mask 2 at 10. The short end 11 is cut out, as at 12, in Fig. 3, to leave a tongue 13 insertible through the slit 6 and then pasted to the front of the mask 2. The tongue 13 makes a rounded edge for the slit 6 and 70 avoids the sharp edge at the entrance to the pocket 8.

Insertible and removable into and from the pocket 8, is a calendar pad 14 which consists of the usual pages bearing the designations 75 of the months and days of the year. The front of the calendar pad 14 has a cover piece, illustrated in Fig. 1, which is folded back when it is desired to expose the first month and this cover, together with a suitable number of the pages, is inserted into the pocket 8 while the remaining pages simply hang in position on the front of the calendar as plainly illustrated in Fig. 2. The back of each of the pages of the calendar pad, is 85 ruled and numbered so that data of various kinds may be written on the back of the page. The calendar pad is made removable for this purpose, and is adapted to be taken out of the pocket 8 in order that the data or memoranda 90 may be more conveniently written thereon.

Rings 15 hold the pages of the calendar pad 14 together. The rings 15 are made preferably as integral parts of a bar or brace 16 spanning the rings as illustrated in 95 Fig. 1, and providing a brace imparting rigidity to the calendar pad 14 when the same is handled. The calendar pad is of course flexible and it can readily be understood that in handling the pad were it not 100 for the bar 16, the pad would collapse in the hand and become inconvenient to handle. By providing the rings 15 with the bar 16 extending across the upper edge of the pad, the pad is made rigid or substantially so, 105 and can be handled very much more easily than would be the case otherwise.

While the construction of the calendar is thought to be fully understood from the foregoing, a resumé of the advantages is 110 thought desirable. It is a common experience with those who have frequent access to

calendars, that the calendar is taken from the wall and to a table or stand where memoranda may be perused or written more readily around a space either in the current 5 month or some future month. This practice prevails more especially in the home and has led to the making and marketing of calendar devices known as "desk pads" which are constructed especially with a view 10 of leaving enough space for written memoranda over each day of the month. Returning again to the first instance, the ordinary wall calendars have insufficient space around the printed date to hold written memoranda 15 of any length.

The calendar described in the foregoing embodies all of the features and advantages of the so-called "desk pad" in that, there is sufficient space on the back of each page 20 to hold a considerable amount of written matter. The calendar also has the advantage that the part which is to contain the written matter, may be transported to a convenient place, thus avoiding the necessity 25 of standing at the place where the calendar is hung. The calendar pad 14 is simply taken out of the pocket 8, the written memoranda is made on the back of the desired one of the pages bearing the month's designation 30 and in the correspondingly numbered space, and then returned to the pocket 8. The removable pad also provides a condensed form for filing and preservation of memoranda.

35 While the construction and arrangement of the calendar as illustrated in the accompanying drawings is that of a generally preferred form, obvious modifications and changes may be made without departing

from the spirit of the invention or the scope 40 of the claims.

I claim:—

1. A calendar pad adapted to be thrust into the pocket of a suitable back, certain of the pages hanging on the front and exposing months' designations, but having divided spaces for written memoranda on the back, the other pages constituting the pad supporting means; and combined means for holding the pages together and stiffening 50 the pad.

2. A calendar pad consisting of a plurality of loose pages having months' designations printed on the front and divided spaces printed on the back for written memoranda, and combined means for holding the loose pages together and stiffening the pad, those pages bearing expired months' designations being turned back to provide a pad mounting, while the other pages hang 60 in front; said means comprising a bar with rings formed on the ends.

3. A calendar pad, consisting of a plurality of pages, loosely combined on common stiffening means, the pages which are 65 turned back with the expiring months constituting the means which supports the pad on a suitable mounting.

4. A calendar pad, consisting of a plurality of pages, with stiffening means on 70 which they are loosely mounted for turning back, the turned back pages constituting the supporting means of the pad when inserted in a suitable support, the pad being removable therefrom to permit turning back the 75 pages.

JESSE E. MELTON.
